UNITED STATES PATENT OFFICE.

JAMES S. LAMAR, OF AUGUSTA, GEORGIA.

TELEGRAPHIC RELAY.

SPECIFICATION forming part of Letters Patent No. 300,269, dated June 10, 1884.

Application filed February 19, 1884. (No model.)

To all whom it may concern:

Be it known that I, JAMES S. LAMAR, a citizen of the United States, residing at Augusta, in the county of Richmond and State of Georgia, have invented certain new and useful Improvements in Relays or Telegraphic Receiving-Instruments; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a side view of a relay-instrument, partly in section, illustrating this invention. Fig. 2 is a plan view of the same.

This invention has relation to relays or telegraphic receiving-instruments; and it consists, essentially, in a vibratory steel magnet acting by its own attraction upon the core of an electro-magnet to break circuit, and by means of the mutual repulsion between said electro-magnet and said steel magnet to make circuit; in the device of a steel magnet so pivoted that it may freely oscillate between stops, and so adjusted and arranged that one of its poles shall embrace within the field of its own magnetism the soft-iron core of an electro-magnet, so connected with its battery or other source of electrical supply that the magnetism of its core produced by the electrical current shall cause the steel magnet to be repelled, the successive attractions and repulsions between the two magnets causing the steel magnet to oscillate between said stops, so as to produce telegraphic signals; in the device of a metallic projection or arm rigidly connected at an angle with a steel magnet, which is caused to oscillate by the successive attractions and repulsions between said steel magnet and an electro-magnet, said arm being furnished with a point of platinum or other metal adjusted to make and break electrical connections, or to produce telegraphic signals; in the combination, with an oscillating steel magnet operating with an electro-magnet to make and break circuit, of a receptacle containing mercury, with which a metallic point connected to said steel magnet is made successively to make and break circuit; in the combination,

with an oscillating steel magnet operating with an electro-magnet to make and break circuit, of a mercury-chamber, a metallic point 55 in connection with the steel magnet, and a governing-screw working in a passage of the mercury-chamber to adjust the height of the mercury with reference to the operation of said metallic point; and in the general combination, with an adjustable electro-magnet connected with the main circuit, of a vibratory steel magnet having an arm in the line of the local circuit, and a pole in attractive relation with the core of the electro-magnet, a mercury-chamber, and an adjusting device to regulate the height of the mercury in the chamber, all as hereinafter set forth.

In the accompanying drawings, the letter A designates the base of the instrument, and B 70 an electro-magnet, which is preferably made adjustable.

C represents a thumb-screw, working in a bearing, D, and adapted to move the electro-magnet when turned.

F F indicate binding-posts for the line-wire a a, with which the electro-magnet is in circuit.

G represents the soft-iron core of the electro-magnet.

H represents a steel magnet, having a pivot, b, seated in bearings e, which are preferably made adjustable by employing screws for the purpose. The steel magnet is provided with a rigid arm, K, which extends at an angle 85 with the magnet, and said arm is provided with a downwardly-extending point of platinum or other metal, as indicated at d. The steel magnet is designed to extend downward, its end e being near the end g of the soft-iron 90 core of the electro-magnet.

L represents a block of iron having the horizontal chamber h, formed with an aperture at k. The end of this chamber is closed by means of a neatly-fitting screw, l. A threaded perforation, m, extends to the chamber h at a distance from the aperture k, and in this perforation is placed a governing-screw, n. The point d of the arm of the steel magnet is designed to extend downward into the aperture k, and in 100 the chamber h is placed sufficient mercury to fill the horizontal portion of said chamber. The height of the surface of mercury in the aperture k is regulated by means of the screws

l and *n*, the latter being employed for the nice adjustment required. Adjustable stops *s* and *t* are employed to limit the movements of vibration of the steel magnet.

5 *N N* represent binding-posts for the wires *z z* of a local battery. From one of these posts the local circuit extends by a brass standard, *S*, to the pivot-bearings of the magnet *H*, and when the point *d* of the magnet is in contact 10 with the mercury, the circuit extends through the magnet-arm and mercury and down by a brass standard, *S'*, to the other binding-post. When the point *d* of the steel magnet is not in contact with the mercury, the local circuit is 15 open. In this relay the polarity of the end *g* of the soft-iron core of the electro-magnet is to be similar to that of the end *c* of the steel magnet, and therefore the binding-posts *F F* are to be so connected with the wire of the main 20 line that the current passing through the coil of the electro-magnet shall produce in its core at *g* the same polarity as that of the steel magnet at *c*. The electro-magnet is to be adjusted by means of the thumb-screw until the steel 25 magnet is freely drawn by its own magnetism toward the end *g* of said core. This movement of the magnet *H* will lift its arm and move the point *d* out of connection with the mercury, opening the local circuit. When the main circuit is closed, the end *g* of the core of the electro-magnet and the end *c* of the steel magnet having the same polarity, the end *c* will be 30 driven by magnetic repulsion away from *g*, vibrating the steel magnet outward and bringing 35 the point *d* of the magnet-arm down into the mercury and closing the local circuit. When, however, the main circuit is open, the end *g* of the core of the electro-magnet having no polarity, the magnetism of the steel magnet 40 *H* will cause it to be drawn toward said end *g*, thus lifting the point *d* from the mercury and opening the local circuit. The arm *K* of the steel magnet is not designed to be perfectly 45 counterbalanced, but should have a slight excess of weight, which is readily lifted by the permanent magnet when the main circuit is open, and when the current is introduced this excess of weight assists the repulsive effort of the electro-magnet in throwing off the steel 50 magnet. The weight of this arm will suffice to control the circuit even when the current in the electro-magnet is barely sufficient to neutralize the magnetism induced in said electro-magnet by the steel magnet; but in actual 55 work a somewhat stronger current should be used, so as to furnish a margin for possible variations in its strength.

This relay is designed to effect a great saving of battery-power. It does not require adjustment to preserve uniformity of action, notwithstanding variations in the strength of the line-current. The margin of admissible variation ranges from the feeblest current that will do the work up to a current of any degree of strength below that which would reverse the polarity of the steel magnet. The device utilizes the principle that two mag-

netic poles of the same name will mutually repel, although one of them may be too feeble to manifest any useful attraction for soft iron. 70 Its capacity is designed to be sufficient to operate a local battery in ocean telegraphy, thereby facilitating and expediting the reception of cable messages.

I am aware that relays have been constructed 75 with a permanent magnet for the core, and provided with a soft-iron armature, and that relays have been made in which both the armature and the core are permanently polarized.

I am also aware that a permanent magnet, 80 as the armature of an electro-magnet having its poles opposite each other, so that while one pole will attract the permanent magnet the other will repel, is not new; also, that permanent magnets serving as annunciator-drops 85 have been used as armatures and held by their own magnetism to the soft-iron core of an electro-magnet when the line-circuit is broken, and repelled when the electro-magnet is energized by the line-current; but said armatures 90 have not been used in relays in this connection, as they controlled no local circuit.

I am also aware that an electro-magnet with a permanent steel magnet for an armature having a counterpoise and spring has been heretofore used; but in such device the principle 95 of operation is entirely different from my relay; and I am further aware that a telegraphic instrument having a soft-iron core and a permanent magnet as an armature which is repelled from the core when the line-current is of a certain polarity is not new; but in such device the permanent steel magnet is not held 100 to the core solely by its own magnetism. Therefore I do not claim such devices; but, 105

Having described this invention, what I claim, and desire to secure by Letters Patent, is—

1. In a telegraphic relay, the combination, with its electro-magnet, of a vibratory steel 110 magnet operated by its own attraction alone toward the core of the electro-magnet to break circuit, and by means of the magnetic repulsion between said steel magnet and the electro-magnet to make circuit, substantially as 115 specified.

2. In a telegraphic receiving-instrument without retractile spring, a permanent magnet as the armature of an electro-magnet normally held thereto by its own magnetism alone, 120 in combination with an arm rigidly attached to said armature to control the local circuit by its own weight when the magnetism induced in said electro-magnet by said armature is neutralized by the line-current, substantially as 125 specified.

3. In a telegraphic receiving-instrument, the combination, with an electro-magnet, of a vibratory steel magnet having a metallic projection or arm rigidly connected at an angle 130 with said steel magnet, and having a point of platinum or other metal adjusted to make and break electrical connections when operated by the successive repulsions and attractions be-

tween said steel magnet and the electro-magnet, substantially as specified.

4. In a telegraphic receiving - instrument, the combination of an electro-magnet, of an oscillating steel magnet, H, arm K, extension d, and mercury-cup h, substantially as and for the purpose specified.

5. In a telegraphic receiving - instrument, the combination of an electro-magnet, an os-

cillating magnet, H, arm K, extension d, mercury-cup h, and governing-screw l, substantially as shown and described.

In testimony whereof I affix my signature in presence of two witnesses.

JAMES S. LAMAR.
